UNITED STATES PATENT OFFICE

147,819

DESIGN FOR A DOUBLE DRAIN TUB OR SIMILAR ARTICLE

Thomas R. Smith, Newton, Iowa, assignor to The
Maytag Company, Newton, Iowa, a corporation
of Delaware

Application January 10, 1946, Serial No. 125,427

Term of patent 14 years

(Cl. D4—2)

To all whom it may concern:

Be it known that I, Thomas R. Smith, a citizen of the United States, residing at Newton, in the county of Jasper and State of Iowa, have invented a new, original, and ornamental Design for Double Drain Tub or Similar Article, of which the following is a specification, reference being had to the accompanying drawing, forming a part thereof.

In the drawing—

Fig. 1 is a perspective view of a double drain tub or similar article showing my new design; and

Fig. 2 is a top plan view thereof.

I claim:

The ornamental design for a double drain tub or similar article, substantially as shown.

THOMAS R. SMITH.
